UNITED STATES PATENT OFFICE.

WILHELM SCHMIDT, OF WILHELMSHÖHE, GERMANY.

DOUBLE-ACTING STEAM-ENGINE.

SPECIFICATION forming part of Letters Patent No. 535,864, dated March 19, 1895.

Application filed June 8, 1894. Serial No. 513,942. (No model.)

To all whom it may concern:

Be it known that I, WILHELM SCHMIDT, a subject of the King of Prussia, German Emperor, and a resident of Wilhelmshöhe, 5 near Cassel, in the Province of Hesse-Nassau, German Empire, have invented certain new and useful Improvements in Double-Acting Steam-Engines, of which the following is an exact specification.

This invention relates to a double-acting steam-engine, the manner of working of which is similar to that of a compound-engine with receiver. There are, however, the differences, that one side of the low-pressure is constantly 15 under the influence of the low-pressure steam piston, and that the space between that side of the low-pressure piston and the opposite cylinder-cover forms part of the receiver, the capacity of the latter being, therefore, a variable one.

The objects of my invention are, first, to provide an engine, which is specially adapted for the use of superheated steam, and, second, to cause in such engine the high-pressure cylinder to be cooled by the low-pressure steam, and the low-pressure cylinder to be heated by the receiver-steam, as will all be more fully described hereinafter.

In order to make my invention more clear, 30 I refer to the accompanying drawing, in which is shown a longitudinal section through an engine constructed according to my invention.

In the figure, *a* is the high-pressure cylinder, within which works the hollow high-pressure 35 piston *a*³ of plunger-like configuration. This piston extends into the low-pressure-cylinder, and carries at its end the low-pressure piston *b*³, by which latter the said cylinder is divided into two compartments or chambers *b*¹ *b*². Chamber *b*² extends, as a matter of course, up 40 into the hollow plunger, and constitutes the variable-receiver-part mentioned in the preamble. This part is in constant communication with the receiver proper *c* by a port *d*, while the high-pressure cylinder *a* and the 45 annular chamber *b*¹ of the low-pressure cylinder are alternately brought into communication with the receiver proper *c* by the hollow slides *e* and *f*. These slides are made integrally, and are operated simultaneously by one and the same valve-rod *g*.

Supposing the valves be in their highest po-

sition, the high-pressure steam entering the engine at *h* will flow into cylinder *a* through the groove around the contracted portion of valve *e*, and through the channel *i*. During this time, the low-pressure steam contained within the receiver will flow into the annular chamber *b*¹, acting therein on a piston-surface of a size like the difference between the working-surfaces of the two pistons. As, now, also chamber *b*² is (constantly) filled with the low-pressure steam, there is, consequently a pressure counteracting the pressure of the high-pressure-steam, the said counteracting pressure being produced by the influence of the low-pressure steam upon the lower side of the high-pressure piston. During the expansion-period the valves *e f* are in their middle position, as shown in the drawing. If, thereafter, the valves are lowered, the high-pressure cylinder will come into communication with the receiver proper *c*, while chamber *b*¹ of the low-pressure cylinder communicates through the outlet *k* either with the atmosphere, or with a condenser. The chambers *a* and *b*², as well as the receiver, are, thus, filled with steam of equal pressure, and the piston on its return stroke is acted on by a pressure constituted by the influence of the low-pressure steam on a piston-surface of a size like that of the difference between the working-surfaces of the two pistons.

Besides the chamber *b*² of the low-pressure cylinder, also the annular space *c*' around the high-pressure cylinder forms part of the receiver. Therefore, the latter cylinder as well as the small piston is constantly cooled by the low-pressure steam present within said space *c*', while the low pressure steam present 85 within chamber *b*² constantly heats the low-pressure cylinder as well as the large piston. By reason of these functions of said spaces, the engine is specially adapted to be driven by superheated steam. There is, then, the 90 further advantage, that stuffing-boxes may entirely be dispensed with.

Having thus fully described the nature of this invention, what I desire to secure by Letters Patent of the United States is—

1. In a steam-engine having two co-axial cylinders of different diameter, and two corresponding pistons dividing the said cylinders into three compartments, the combina-

tion with a receiver, constantly communicating with the outer compartment of the larger cylinder, and with a valve adapted to connect the smaller cylinder alternately with the inlet and with said receiver, of another valve adapted to connect the middle compartment alternately with the receiver and with the outlet, for the purpose as described.

2. In a steam-engine having two co-axial cylinders of different diameter, and two corresponding pistons dividing the said cylinders into three compartments, the combination with a receiver, constantly communicating with the outer compartment of the larger cylinder, and with a valve adapted to connect

the smaller cylinder alternately with the inlet and with said receiver, of another valve adapted to connect the middle compartment alternately with the receiver and with the outlet, the port operated by said latter valve being adapted to lead the steam into the said middle compartment, as well as out of the same, for the purpose as described.

In testimony whereof I have signed this specification in the presence of two subscribing witnesses.

WILHELM SCHMIDT.
